LIGHTING MEANS FOR PHONOGRAFS AND
THE LIKEAndrew B. Christensen, North Tonawanda, N. Y.,
assignor to The Rudolph Wurlitzer Company,
North Tonawanda, N. Y., a corporation of Ohio

Application October 4, 1937, Serial No. 167,219

1 Claim. (Cl. 240—10.1)

This invention relates generally to certain new and useful improvements in lighting devices or systems but more particularly to devices for creating novel lighting effects in the record playing compartments of automatic phonographs.

One of its objects is to provide a lighting system of this character which is designed to create variegated lighting effects or displays and enhance the beauty and appearance of the phonograph or like instrument to which it is applied.

Another object of the invention is to provide, in combination with a reflecting wall or background, a revolvable light-emitting means or screen for directing moving beams of colored light rays across the background to create novel and distinctive lighting effects.

Other features of the invention reside in the construction and arrangement of parts herein-after described and particularly pointed out in the claim.

In the accompanying drawings:

Figure 1 is a fragmentary front view of the record-playing compartment of an automatic phonograph equipped with my invention. Figure 2 is a detached front view of the reflecting background showing a lighting display therein and the revolving light source or screen employed in connection with my invention. Figure 3 is an enlarged rear elevation of the light source unit. Figure 4 is a sectional elevation showing the relative arrangement of the reflecting background and the revolving light unit. Figure 5 is a side elevation of the variegated color drum or screen of the light unit.

Similar characters of reference indicate corresponding parts throughout the several views.

This invention has been designed more particularly for application to the record-playing compartments of automatic phonographs and such application of it is shown in the drawings, the numeral 10 indicating the upper portion of the phonograph cabinet, 11 the compartment in which the customary record-changing mechanism is mounted, 12 the glass-paneled door thereof and 13 the platform or floor of such compartment. Mounted on this platform are a plurality of horizontally-swinging record-carriers 14 which are adapted to be swung to and from a playing position over the vertically-movable turntable 15 and into and out of playing engagement with the customary needle of the tone arm 16.

Disposed at the rear of the compartment 11 is an upright wall 17 constituting the light-projection surface or background upon which the variegated lighting effects are produced and

whose reflecting surface may be finished to represent quilted maple or other appropriate finish. The rear edge of the platform 13 terminates short of the wall 17 to provide a light-projection opening 18 and disposed substantially centrally below the platform adjoining such opening is the revolving light-emitting unit whose parts are mounted on a bracket 19 secured to a portion of the interior of the cabinet 10. Constituting a part of this unit is a revolvable light-emitting screen or cylinder 20 having its axis disposed at right angles to the plane of the wall 17 and secured to a horizontal shaft 21 driven by an electric motor 22 suitably secured to the bracket. One end of this cylinder is provided with a shaft-attaching plate 23, while its opposite or rear end is open and extending into the same is an electric lamp 24 fitted in a socket-bearing arm 25 adjustably secured to the bracket 19 by a screw 26. If desired, the drum-plate 23 may be provided with vent openings 27 for the dissipation of the heat from the lamp.

The body of the cylinder 20 is made of a suitable transparent material for the passage of the light rays from the lamp 24 and formed on this cylinder and extending in the direction of its axis are a plurality of parallel colored bands or stripes 28, such as red, green and purple, or other color-combinations to produce the lighting effect desired. These colored stripes are arranged side by side and extend continuously about the cylinder in any desired order or arrangement, depending on the lighting effect and color scheme to be produced on the screen-wall 17. As the cylinder 20 revolves, the colored light beams emanating from the stripes 28 are directed against and imposed upon the wall 17 from end to end thereof in the general shape of a fan with the individual colored sectors 29 thereof diverging radially outwardly from the lower portion of the wall. In the lighting effect shown in Figures 1 and 2 of the drawings, by way of example, the color and arrangement of the stripes 28 are such as to create or simulate a peacock effect on the wall 17. To further reproduce this effect, the cylinder is preferably provided with openings 30 at different points about its circumference, as seen in Figures 4 and 5, and the light passing through these openings is reflected on the wall in the form of substantially oval or elongated light spaces 31, thereby creating, as a whole, a very striking and beautiful lighting display within the compartment 11. Furthermore, as the cylinder revolves at a slow speed, the lighting effect is continuously changed and a variegated

color scheme of a very attractive and pleasing design is reflected against the background wall.

In practice, the lamp 24 and the motor 22 for rotating the cylinder 20 are included in the 5 operating circuit of the phonograph, so that when the latter is rendered operative for play the lighting display within the compartment 11 is also made effective.

While this invention has been particularly designed for and is shown in connection with the record playing compartment of the phonograph, it is to be understood that the invention is equally applicable to other portions of the phonograph where similar lighting effect is to be displayed.

10 15 I claim as my invention:

A lighting display for the record-playing compartments of phonographs, comprising a background upon which the light display is adapted to be directed, a revolving cylinder of light-translucent material disposed beneath and in a plane 5 forwardly of said background and having a plurality of colored stripes thereon arranged at substantially right angles to the background in parallel relation to the cylinder-axis and interspersed with openings, and a light source arranged within said cylinder, whereby the light rays are directed on the background in a fan-like colored display interspersed with light spaces.

10 15 ANDREW B. CHRISTENSEN. 15
